HEADLIGHT DOOR REMOVER AND REPLACER

Filed March 27, 1926

Patented June 21, 1927.

1,633,528

UNITED STATES PATENT OFFICE.

JOHN W. HELLER, OF ARLINGTON, KANSAS.

HEADLIGHT-DOOR REMOVER AND REPLACER.

Application filed March 27, 1926. Serial No. 97,934.

This invention relates to devices for removing the doors of headlights such as are used on automobiles. These doors are, in the great majority of cases, removable by 5 pressing the door inward and then turning it to the left. This is a somewhat difficult operation without proper tools for the purpose, particularly when the headlight door fits very tightly upon the body of the headlight and the general object of the invention is to provide a very simple appliance whereby the door may be evenly pressed inward at a plurality of points and whereby the door may be turned to the left and removed.

10 A further object is to provide a device of this character which is adapted, without adjustment, for slight variations in the diameter of the headlight door and which is further adjustable for larger variations.

15 Other objects will appear in the course of the following description.

My invention is illustrated in the accompanying drawings wherein:

Figure 1 is a face view of my door remover applied to a headlight door;

Fig. 2 is a section on the line 2—2 of Figure 1;

Fig. 3 is a section on the line 3—3 of Figure 1;

20 Fig. 4 is a fragmentary diagrammatic sectional view enlarged to show divergence of the two rivet engaging members;

Fig. 5 is an enlarged fragmentary elevation of the inside face of one of said rivet engaging members.

25 Referring to these drawings it will be seen that my improved door remover comprises a longitudinal extending rod 10 which at one end is rigidly connected to a wider relatively flat elongated strip 11. This strip at one end projects beyond the member 10 a relatively slight distance and at its other end projects a relatively long distance, this last named end being apertured as at 12. The opposite end of the member 10 from the member 11 is screw-threaded and carries upon it the inner and outer nuts 13, it being understood that the outer nut may be in the form of a wing nut.

30 Coacting with the members 10 and 11 is an L-shaped member consisting of a longitudinally extending rod 14 parallel to the rod 10, and a strip 15 having the same width and length as the strip 11 and permanently joined to the member 14 and extending at right angles thereto. This strip 15

is apertured above its extremity for the passage of the rod 10, the nuts 13 engaging on each side of the strip 15. The rod 14 fits loosely within or has sliding engagement 60 through the opening 12.

The inner faces of the lower ends of the strips 11 and 15 are formed each with a pair of grooves 16 opening upon the adjacent ends of the strips. These grooves are transversely curved or concave, and open upon the ends of the strips 11 and 15 respectively. The strips 11 and 15 are not parallel to each other transversely but a slight twist is given to these strips so that the strips are about 70 $1/32''$ nearer to each other at one lateral margin than they are at the opposite margins, as shown in Figure 4.

The grooves 16 are designed to accommodate and receive the rivets on the headlight 75 door. Mounted upon the rod 10 is a cross bar 17 having rounded ends and having any desired width such, for instance, as the width of strips 11 and 15 and this cross bar at its middle is formed to swing upon the member 10 and extend below said member. Thus this cross bar may have a medially deflected portion 18 through which the rod 10 will pass and constituting a pivotal support for this cross bar 17.

80 It will be seen that this door removing device comprises two opposed and approximately parallel members 11 and 15, that both of these members are formed with longitudinally extending grooves 16 on their inner confronting faces, that the members 11 and 15 are adjustable toward or from each other by means of the nuts 13 on the rod 10, and that this rod is disposed adjacent the like ends of both strips or members 11 and 15 and adjacent the inner ends of the grooves 16. It is also pointed out that the outer face of the part 17 or cross bar, that is, the face which bears against the face of the door, is approximately in the same plane 90 with the ends of the rod 10 and that thus a four-point bearing is secured against the face of the door, namely, at the two ends of the rod 10 and adjacent opposite ends of the transverse bar 17.

95 In the use of this device the cross bar 17 is adjusted upon the rod 10 so as to extend diametrically across the door of the headlight and then the device is slipped upon the door so that the grooves 16 of the two strips 11 and 15 will slip over the two rivets on the door, then pushed inward against the door 100 110

by leaning against the rod 14 until the device has four points of contact with the door namely, the ends of the cross bar 17 and the ends of the rod 10. After the door has been pushed inward sufficiently then the device is to be turned to the left which will turn the door to the left thus shifting the pins 19 of the door ring out of the bayonet slots 20 of the headlight casing and then the door becomes detached from the headlight body but yet is held in the grooves 16 by the rivets of the door. By slightly deflecting the extremities of the members 11 and 15, as illustrated in Figure 4, the device may be used on two or more sizes of door without making an adjustment of the nuts 13 or in other words, without shifting the member 15 and its rod 14 with the rod 10 and member 11. Obviously when larger adjustments are to be made the nuts 13 are to be turned so as to carry the member 15 inward or toward the member 11 or outward and away from member 11. Obviously the member 17 will be shifted to a point midway between the members 11 and 13 before they are adjusted so that this member 17 will extend diametrically across the headlight door and bear at opposite points thereagainst.

39 The device is simple, may be readily adjusted to all sizes of headlight doors and will quickly remove the door without any damage thereto.

I claim:

- 35 1. A device for removing headlight doors comprising two opposed approximately parallel members having longitudinally extending grooves upon their inside confronting faces, a rod connecting said members and having means whereby one of the members may be forced toward the other, and a cross bar pivotally mounted upon the rod midway between said members, the cross bar having one face thereof at its ends disposed in the same plane as the ends of said rod.
- 40 2. A device for removing headlight doors comprising two oppositely disposed approximately parallel members having their confronting faces grooved, the grooves extending inward from the like ends of the members, a rod adjustably connecting said members and disposed adjacent the inner ends of the grooves the ends of said members remote from the rod being adjustably engaged by a second rod approximately parallel to the first named rod, and a cross bar mounted

upon the first named rod midway between its ends, said cross bar extending at right angles to the rod upon which it is mounted, one face of the cross bar being disposed approximately in the same plane as the ends of the rod.

3. A device of the character described comprising a relatively flat strip having a rod engaged therewith and extending at right angles therefrom, the rod being disposed adjacent one end of the strip and this end of the strip having longitudinally extending grooves on its inner face opening upon the adjacent end of the strip, said rod being screw-threaded at its end remote from the strip and having a pair of nuts thereon, a second relatively flat strip having an aperture adjacent one end thereof through which said rod passes, said strip being engaged on opposite faces by said nuts, said strip at its end remote from the rod having a second rod extending parallel to the first named rod and passing loosely through an opening in the first named strip, the inner face of the second named strip having grooves extending from the first named rod to the adjacent end of the strip remote from said first named rod, the strips being disposed in slightly diverging relation, and a cross bar pivotally mounted upon the first named rod and extending at right angles thereto, the cross bar being adjustable along the rod and having one face thereof at its ends disposed in the same plane as the ends of said rod.

4. A headlight door remover and replacer comprising two confronting clamping strips adapted to engage the periphery of a headlight door between them, the confronting faces of said strips adjacent one end of each strip being formed with a plurality of grooves adapted to receive the rivet heads on the door, and a rod extending approximately at right angles to the plane of the strips and engaged with one strip and passing loosely through the other strip and having nuts engaged on each side of the last named strip whereby said strips may be drawn together, and a cross bar pivotally mounted upon the rod and extending at right angles thereto and adapted to bear against opposite points on the face of the headlight door.

In testimony whereof I hereunto affix my signature.

JOHN W. HELLER.
